CANDLE HOLDER

Jens H. Quistgaard, Lucern, Switzerland, assignor to Dansk Designs-With-Light, Inc., Great Neck, N.Y., a corporation of New York

Filed May 24, 1961, Ser. No. 65,318

Term of patent 14 years

(Cl. D48—2)

FIG. 1.

FIG. 2.

FIG. 3.

FIG. 1 is a front elevational view of a candle holder showing my new design;

FIG. 2 is a top plan view thereof; and

FIG. 3 is a bottom plan view.

The side of the candle holder not shown is substantially the same in appearance as the side shown.

I claim:

The ornamental design for a candle holder as shown and described.
